TRACTION BELT FOR VEHICLE TIRE

Joseph Horton Wellings, 55 Mount Ave.,
Erling, London, W. S, England

Filed Aug. 15, 1975, Ser. No. 605,042

Claims priority, application Great Britain Feb. 17, 1975

Term of patent 14 years

Int. Cl. D12—16

U.S. CL. D12—154

Fig. 1.

Fig. 2.

Fig. 4.

FIG. 1 is a side elevational view of a traction belt for a vehicle tire showing my new design;

FIG. 2 is an end elevational view thereof; and

FIG. 3 is an enlarged fragmentary perspective view thereof; and

FIG. 4 is a greatly enlarged cross sectional view thereof taken along line IV-IV in Fig. 1.

I claim:

The ornamental design for a traction belt for vehicle tire, as shown.
